ANDREW RAICHE, OF FAIRHAVEN, MASSACHUSETTS, ASSIGNOR TO ATLAS TACK COMPANY, OF FAIRHAVEN, MASSACHUSETTS, A CORPORATION OF NEW JERSEY.

GANG-HOOK-SETTING MACHINE.

1,146,952.

Specification of Letters Patent.

Patented July 20, 1915.

Application filed June 12, 1911. Serial No. 632,573.

To all whom it may concern:

Be it known that I, ANDREW RAICHE, of Fairhaven, in the county of Bristol and State of Massachusetts, have invented certain new and useful Improvements in Gang-Hook-Setting Machines, of which the following is a specification.

This invention relates to machines for inserting lacing hooks in the uppers of boots 10 and shoes.

The invention comprises a plurality of hook-sustaining members and an equal number of anvils, whereby a plurality of hooks may be simultaneously inserted and 15 clenched in the work.

One of the objects of the invention is to provide improved means for varying the spacing of the hooks. This is accomplished by mounting the hook-sustaining plates 20 upon individual supports which are movable radially toward and from a common center, and by mounting the several anvils in like manner. The positions of the hook-sustaining plates and anvils are adjusted 25 by mechanism which moves them simultaneously and equally toward or from the common center about which they are disposed.

Another object of the invention is to provide improved means for placing lacing 30 hooks in position upon the sustaining plates.

The placing of the hooks is effected by a plunger which transfers the hooks one at a time from the lower end of a raceway to the several plates. The plunger has two 35 movements, one of which is its transferring movement and the other of which is a step-by-step movement about an axis whereby it is caused to register successively with the several hook-sustaining plates. The

40 plunger, after transferring a hook from the raceway to the first plate, is turned about its axis so that it will register with the next plate, and is then reciprocated for the purpose of transferring another hook to the 45 next plate. In this way the hooks are placed upon the several hook-sustaining plates in position to be inserted in the work.

Another object of the invention is to operate the setting mechanism and the loading 50 mechanism in such manner as to save time in the operation of the machine. This object is carried out in the following manner: The setting mechanism and loading mechanism are operated at different times, each 55 mechanism being out of operation when the

other is in operation. When the machine is at rest, the several hook-sustaining plates are provided with hooks and the setting mechanism is in position to insert the hooks in the work. The setting mechanism is set 60 in operation by a manually controlled clutch. When the setting mechanism has completed its cycle of movements, its clutch is automatically disconnected and the loading mechanism is automatically set in operation by other clutch mechanism which is controlled by the shaft which drives the setting mechanism. The work is free to be removed from the machine at the completion 65 of the setting operation, and a new 70 piece of work may be placed in position during the period of time in which the loading mechanism is being operated. The loading mechanism is automatically disconnected from the driving means after 75 having completed its cycle of movements, thus leaving the entire machine at rest after having provided the several hook-sustaining plates with hooks in position to be inserted in the work when the setting mechanism is again set in operation. In this embodiment of the invention the setting mechanism and loading mechanism are operated 80 by separate shafts, each having independent clutch mechanism, and the clutch mechanisms are controlled in the following manner. When the shaft for the setting mechanism has completed one revolution, its clutch is automatically disconnected and it causes the setting of the clutch which controls the shaft for driving the loading mechanism. The clutch for the second shaft is automatically disconnected when the shaft has completed one revolution, thus leaving both shafts disconnected from their 85 sources of power. The advantage of controlling the machine in this manner is that no time is lost while the operator is removing one piece of work and inserting another piece of work, for the period of time for removing and inserting the work is utilized by the loading mechanism in placing the hooks in position to be inserted in the work without delay upon subsequent starting of the machine.

Of the accompanying drawings which illustrate one form in which the present invention may be embodied: Figure 1 represents a left side elevation of the complete machine, the hook reservoir being partly in 110

section. Fig. 2 represents an elevation of the mechanism for distributing the hooks one by one to the several hook-sustaining plates. Fig. 3 represents a vertical section on the plane indicated by line 3—3 in Fig. 2. Fig. 4 represents a horizontal section of the machine in a plane indicated in Fig. 1 by line 4—4. Fig. 4^a represents a section of clutch-controlling mechanism for the loading mechanism. The plane of the section is indicated in Fig. 4 by line a—a. Fig. 5 represents an elevation of mechanism for causing the hook-distributing mechanism to register with the several hook-sustaining plates. Fig. 6 represents a top plan view of the hook-sustaining plates, the lower end of the hook race, and the hook-distributing mechanism. Fig. 7 represents a top plan view of portions of the hook race and distributing plunger. Fig. 8 represents a top plan view of a portion of the hook-distributing plunger in the act of carrying a hook. Fig. 9 represents a front elevation of the lower end of the hook race, with a hook in position to be carried forward by the distributing plunger. Fig. 10 represents a view similar to Fig. 9, showing the distributing plunger in cross section closing the lower end of the hook race. Fig. 11 represents a top plan view of the anvil carrier detached from the frame. Fig. 12 represents a perspective view of manually operative means for varying the spacing of the hook setting elements. Fig. 13 represents a perspective view of one of the adjustable hook-sustaining plates with its supporting mechanism. Fig. 14 represents a vertical cross section in a plane from front to rear through one of the hook-sustaining plates, including the operative anvil and a portion of the hook-distributing plunger. Fig. 15 represents a vertical section through the anvil carrier in a plane indicated in Fig. 11 by the line 15—15. Fig. 16 represents a vertical section of the clutch mechanism by which the setting mechanism is driven. Fig. 17 represents a horizontal section through the clutch mechanism shown by Fig. 16. Fig. 18 represents a top plan view of the upper end of the hook raceway.

The same reference characters indicate the same parts wherever they occur.

The mechanism for inserting and clenching the hooks will be described first in preference to the mechanism for distributing the hooks to the setting mechanism, inasmuch as the setting mechanism and distributing mechanism are operated in the order recited when the machine is set in operation. The setting mechanism comprises a plurality of hook-sustaining plates which are arranged substantially radially with reference to a common center. Above the hook-sustaining plates is a plurality of anvils which are mounted upon a carrier, the carrier being

movable vertically toward and from the hook-sustaining plates for the purpose of effecting the insertion and clenching of the hooks supported by said plates. The plates themselves are not movable toward and 70 from the anvils, but they are movable laterally with relation to the setting movements of the anvils for the purpose of releasing the hooks after the setting operation has been performed. The hook-sustaining 75 plates are otherwise movable laterally with relation to the setting movements of the anvils, for the purpose of varying the spaces between the hooks, and the anvils themselves are likewise movable laterally of their setting movement for the purpose of co-operating with the hook-sustaining plates in varying the spacing of the hooks. 80

The frame of the machine comprises a base 20 and upper structure 21 upon which 85 the several mechanisms hereinafter described are mounted. The hook-sustaining plates are indicated at 22, and the anvils which co-operate therewith are indicated at 23. Each hook-sustaining plate is mounted 90 in the manner best shown by Figs. 13 and 14. The plate is mounted upon a block 24 which is provided with guides 25 in which the plate is adapted to slide, so that it may be retracted from the hook upon the completion of a setting operation. The supporting block 24 is formed upon or otherwise secured to a slide 26. The several slides 26 are arranged in guides 27 formed in the forward part 28 of the frame. The 95 several guides 27 are arranged radially with reference to a common center, as shown by Fig. 6. In this embodiment of the invention there are four of such slides 26, but the number may be varied if more 100 or less hooks are required for a shoe. Each slide 26 is provided with teeth 29 constituting a rack. The several slides are positioned in their guides 27 by pinions 30 which co-operate with the rack teeth 29. As 105 shown by Fig. 14, the teeth of the pinions 30 are formed on cylindric members 31 which are suitably mounted in bearings in the portion 28 of the frame. Each member 31 is provided with a second pinion, the 110 teeth of which are indicated at 32. The teeth 32 are engaged by teeth 33 formed upon a segmental bar 34 whose curvature is concentric with reference to the axis from which the guides 27 radiate. When the segmental bar is moved in one direction or the other, the several slides 26 are moved radially toward or from their common center, and in this way the spacing of the several 115 hook-sustaining plates is varied. Similar mechanism for simultaneously adjusting the anvils 23 is hereinafter explained.

The blocks 24 upon which the hook plates 22 are mounted are cut away, as shown by Fig. 14, for the reception of the heads of 120

the hooks *x* and for the reception of pivoted retaining members 35 for engaging the heads of the hooks to prevent their dislodgment from the plates 22. Each block 24 is 5 provided with a socket for the reception of a spring 36, the spring acting upon the retaining member 35 to press said member into engagement with a hook. The several plates 22 are reciprocated in their guides 25 by bell-crank levers 37. The levers 37 are 10 mounted in the slides 26 by means of fulcrum pins 38. The upper end of each lever 37 occupies a hole formed in its respective plate 22. The several plates 22 are normally held in hook-supporting position by 15 springs 39 which act upon the lower arms of the bell-crank levers 37. Retraction of the plates 22 is effected by a plunger 40 at the upper end of which is a head 41 of sufficient area to engage all the bell-crank levers 37 in whatsoever position the said levers may be adjusted.

The plunger 40 is vertically movable in a bearing in the portion 28 of the frame. 25 The lower end of the plunger is connected by a link 40 with an operating lever 42. (See Fig. 1). The lever 42 is mounted upon a fulcrum stud 43 and is provided with a cam roll 44 at its rear end. The cam roll is 30 arranged to be engaged by a cam 45 affixed upon a main power shaft 46. A spring 47 connected to the forward end of the lever 42 normally depresses the plunger 40 and holds the roll 44 against the cam 45. 35 The several anvils 23 are affixed in separate adjustable holders 48, as shown by Fig. 15. Each holder is formed with a horizontal extension 49 which constitutes a slide. The several slides are arranged in guides 50 40 formed in the lower surface of a vertically movable carrier 51. The guides 50 are arranged radially with reference to the same axis from which the guides 27 radiate. The slides 49 are provided with rack teeth 52 45 which are engaged by pinions 53. The teeth of the pinions 53 are formed on cylindric members 54 which have suitable bearing in the carrier 51. Each member 54 has a second set of teeth 55 constituting another pinion. The pinions 55 are engaged by the teeth 56 of a segmental bar 57. The bar 57 is connected, as shown by Fig. 12, with the segmental bar 34 so that the two bars may be moved in unison. One end of each bar 55 projects beyond the member in which it has its bearing. The projecting end of the bar 34 is connected by a link 58 with an arm 59 affixed upon a rock shaft 60. The projecting end of the bar 57 is connected by a link 61 60 with an arm 62 likewise affixed upon the rock shaft 60. An operating lever 63 is affixed to the rock shaft and is adapted to be manually operated so as to effect simultaneous adjustment of the slides 26 and 49, 65 the connecting mechanism for the two sets

of slides being adapted to impart equal movement to all the slides. The lever 63 is provided with a latch 64 which is adapted to coöperate with a notched sector 65, shown by Fig. 4, whereby the several slides 70 are locked in the desired positions. The rock shaft 60 is mounted in suitable bearings in the frame 21, as shown by Fig. 4. In order to provide for vertical movement of the segmental bar 57 when the carrier 75 51 is reciprocated, the link 61 is provided with an elongated pin 61^a which extends through the segmental bar 57 and upon which the said bar may slide.

The anvil carrier 51 is provided with a 80 plunger 66 which is adapted to slide vertically in a suitable guide 67 at the upper part of the frame. The plunger and its guide are preferably angular in cross section, as shown by Fig. 11, for the purpose of preventing rotative movement of the carrier about the axis of its plunger. The upper end of the plunger is connected by a link 68 with the forward end of an operating lever 69. The lever is mounted upon a fulcrum stud 70 supported by the frame. The rear end of the lever is connected with an adjustable connecting rod 71, the lower end of which is provided with an eccentric strap 72 engaging an eccentric 73 on the shaft 46. 95 The work is supported in position to receive a set of lacing hooks by a yielding plate 74. (See Figs. 1 and 14). The plate is provided with a number of pins 75 which are adapted to slide in bearings in a plate 77 affixed to 100 the portion 28 of the frame. Each pin 75 is surrounded by a helical spring 78, the several springs normally elevating the plate 74 so that its upper surface is slightly above the shanks of the hooks supported by the 105 plates 22.

In practice, the several plates 22 will be provided with hooks, as shown by Fig. 14, when the machine is at rest. The operator may then place an upper in position upon the plate 74 and depress a treadle, (not shown) to start the operation of the setting mechanism, whereupon the carrier 51 will be depressed. The plate 74 is cut away to permit the anvils 23 to pass therethrough. The 110 anvils engage the upper surface of the work and press the work upon the shanks of the hooks, which are forced through the work without requiring any holes previously prepared for their reception. The descent of 115 the anvils is continuous, and their upward movement follows immediately upon the completion of the downward movement. At the completion of the downward movement of the anvils, the operating lever 42 is actuated by the cam 45 to raise the plunger 40 and thus effect the retraction of all the plates 22 from the throats of the hooks. As the anvils 23 move upwardly, the work with the hooks clenched therein is slightly raised by 120 125 130

the yielding work plate 74 so that the work is free to be removed from the machine.

Two of the anvil holders 48 are provided with abutments which act as gages for positioning the work with relation to the hooks prior to the descent of the anvils. These abutments are in the form of pins, indicated at 79. Each pin is affixed to a split bushing 80, the bushings being clamped upon the holders 48 by means of screws 81. (See Fig. 11).

Loading mechanism.—The lacing hooks α are supplied by a reservoir 83 of any suitable construction. The reservoir shown by Fig. 15 contains a rotative elevator 84 of well known construction. The hooks which are lifted by the several blades of the elevator descend by gravity through an opening 85 in the wall of the reservoir. The reservoir is 20 provided with a short section 86 of raceway with which the blades of the elevator register successively. This section of the raceway is fixed and serves merely to conduct the hooks from the elevator to a main raceway 87 which is movable. The raceway 87 is 25 affixed at the upper end of an oscillatory carrier 88 mounted in a suitable bearing in the frame, as shown by Figs. 2, 3 and 5. The lower end of the raceway is shown best 30 by Figs. 6 to 10. The carrier 88 has at its upper end a groove which constitutes a bearing for a reciprocating hook slide 89. The axis of the carrier 88 is coincident with the axis from which the slides 26 and 49 radiate. 35 The slide 89 is arranged to move transversely of said axis toward and from the hook-sustaining plates. (See Fig. 6). As shown by this figure, the slide 89 is in alinement with one of the hook-sustaining 40 plates and is retracted therefrom. The operating mechanism by which the slide 89 is reciprocated causes the slide to move toward the hook-sustaining plate to carry a hook from the lower end of the raceway to the 45 plate. The slide is then retracted to the position shown, after which the carrier 88 is moved about its axis so as to cause the slide 89 to register with the next hook-sustaining plate. The hook slide is then reciprocated to 50 transfer a hook to the second plate, after which the carrier 88 is again oscillated to cause the slide 89 to register with the next hook-sustaining plate, and so on until the slide has transferred hooks one by one to 55 each of the hook-sustaining plates.

The operating mechanism illustrated for reciprocating the slide 89 is shown by Figs. 1 and 2. The slide is provided with teeth 90 which are engaged by a gear 91 affixed 60 to a shaft 92 mounted in bearings in the upper end of the carrier 88. A pinion 93 affixed to the shaft 92 engages a rack bar 94 which is mounted to slide vertically in the carrier 88. Yielding connection between 65 the rack bar 94 and an operating lever 95

is made by a plunger 96 and a compression spring 97. The lower end of the plunger 96 is connected with the operating lever 95 in such manner as to provide for limiting oscillatory movement of the carrier 88 about 70 its axis. The lever is mounted upon a fulcrum stud 98 and is provided with a cam roll 99 which coöperates with a cam 100 on a secondary shaft 101. The cam is adapted to impart to the slide 89 sufficient movement to reach the hook-sustaining plates when the latter are farthest from the raceway, and the extensible connection comprising the rack bar 94, plunger 96 and spring 97 is adapted to compensate for shorter 80 movements of the slide when the latter is limited by the hook-sustaining plates in their closer relation to the raceway.

The carrier 88 is oscillated by the mechanism illustrated in Figs. 1, 4 and 5. The carrier is provided with a gear segment 102 which is engaged by the teeth of a rack bar 103. The rack bar is provided with a roll 104 which is engaged by a cam 105 affixed upon the shaft 101. The shape of the cam 90 105 is such as to project the rack bar 103 intermittently in one direction and to retract it continuously in the opposite direction to effect the step-by-step turning of the carrier 88 from its initial position and to return it 95 to said position after having caused the slide 89 to register successively with the several hook-sustaining plates. The hooks α slide from the lower end of the raceway 87 to a raceway extension 106. This extension 100 (see Figs. 7, 8, 9 and 10) is connected by a pivot stud 107 with a bracket 108 affixed to the raceway 87. The free end of the extension 106 is normally held in alinement with the raceway 87 by a spring 109, as shown 105 by Fig. 6. A hook sliding upon the extension 106 is positioned in the line of the slide 89 by a shoulder 110 formed upon the extension. The slide 89 is provided with a hook carrier which comprises a supporting member 111 and a positioning member 112. (See Fig. 8.) The member 112 is forked whereby it provides two fingers adapted to straddle the tubular portion of the hook to hold the hook in the desired position upon 110 the supporting member 111. The member 111 is provided with a notch, as shown by Fig. 7, for the purpose of receiving the hook-retaining member 35 located under the hook-sustaining plate 22. When the slide 115 120 is projected toward a hook-sustaining plate, the hook-carrying members 111 and 112 grasp the hook supported by the extension 106 and displace the extension to the position shown by Figs. 8 and 10. In this way the hook is removed from the free end of the extension, and the mouth of the raceway 87 is closed by the slide 89. The slide is immediately retracted after having carried the hook to a sustaining plate, the hook 125 130

being detached from the carrier by the retaining member 35.

The initial position of the hook-distributing mechanism is that shown by Figs. 1, 4 and 6. In this position the upper end of the raceway 87 is in alinement with the fixed raceway section 86, as shown by Figs. 4 and 18. A yielding stop 113 is provided for preventing hooks from dropping from the section 86 when the raceway 87 is out of register. The stop member is automatically retracted from hook-engaging position when the raceway 87 returns to the position shown by Figs. 4 and 18. The retraction of the stop member is effected by a finger 114 affixed to the raceway 87.

Clutch mechanism.—The shaft 46 by which the setting mechanism is operated is driven independently of the shaft 101 by which the loading mechanism is operated. The shaft 46 is driven by a pulley 115, and the shaft 101 is driven by a pulley 116. The pulleys are driven continuously and are initially free to rotate without driving their respective shafts. Clutch mechanism for driving the shaft 46 is shown by Figs. 16 and 17. The hub of the pulley 115 contains a bushing 117 in which is mounted a sliding clutch member 118. The inner end of the member 118 is adapted to engage any one of a plurality of projections 119 carried by the pulley. The outer end of the member 118 is provided with a head 120 of the shape shown best by Fig. 17. The head 120 is adapted to coöperate in a well known manner with a starting rod 121. The rod is mounted in suitable bearings so as to be movable toward and from the shaft and is normally projected toward the shaft by a spring 122. When the end of the starting rod is in the position shown by Fig. 16, it is adapted to be engaged by the head 120. The clutch member 118, as shown by the drawings, is in driving engagement with one of the projections 119, and the shaft 46 is presumably rotated in the direction indicated by the arrow. The head 120 is provided with an inclined face 123 which will engage the upper end of the starting rod 121. The coaction of the face 123 with the rod effects retraction of the member 118 from engagement with the projection 119, and the rotation of the head 120 is arrested by the rod 121. When the rod 121 is depressed against the tension of its spring 122, the head 120 is released and the clutch member 118 is projected into driving position by a spring 124, shown in Fig. 17. The spring, as shown, is contained in a socket formed in the bushing 117 and acts upon a member 125 rigidly connected by a pin 126 with the clutch member 118. In practice, the starting rod 121 is depressed by a treadle (not shown) and is immediately released so that its spring 122 may return it to the position

shown in the path of the head 120. This mechanism disconnects the clutch and stops the rotation of the shaft at the end of one revolution. The shaft 46 not only drives the setting mechanism, but it controls the clutch by which the shaft 101 is driven.

As shown by Fig. 4, the hub of the pulley 116 contains a bushing 127 in which is mounted a sliding clutch member 128. The member 128 is adapted to engage any one of a plurality of projections 129 carried by the hub of the pulley. The outer end of the clutch member 128 is provided with a head 130 similar to the head 120. The head 130 is adapted to be engaged by a starting pin 131 which is normally held in the path of the head by a spring 132. The head is formed with an inclined face 133 which contacts with the pin 131 to effect the retraction of the clutch member 128. The member 128 is normally thrust into operative position by spring tension means similar to that illustrated by Fig. 17, and the clutch is controlled in the same manner as the clutch for the shaft 46, excepting that the starting pin 131 is moved automatically instead of manually. The shaft 46 carries a disk 140 which is provided with a cam portion 141. The starting pin 131 is provided with a projection 142 which is adapted to be engaged by the cam portion 141 to effect the retraction of the pin. The cam portion 141 is so arranged as to act upon the projection 142 an instant before the shaft 46 is disconnected from its driving pulley, with the result that the clutch for the loading mechanism is operatively connected at the time when the clutch for the setting mechanism is disconnected. The starting pin 131 is released by the cam portion 141 before the shaft 46 comes to rest, and the starting pin 131 is therefore restored by its spring 132 to such position as to effect the disconnection of its clutch at the end of a revolution of the shaft 101.

I claim:

1. A machine for setting lacing hooks, comprising a plurality of hook-supporting members, a plurality of anvils adapted to coöperate therewith to set a plurality of hooks in one operation, said supporting members and anvils being laterally movable for varying the spacing of the hooks, and means connecting said supporting members and anvils whereby they may all be adjusted radially toward and from a common axis to effect the desired spacing.

2. A machine for setting lacing hooks, comprising a plurality of hook-supporting members, a plurality of anvils adapted to coöperate therewith to set a plurality of hooks in one operation, said supporting members and anvils being movable laterally in divergent paths to vary the spacing of the hooks, and means connecting said supporting members and anvils whereby they may

- all be caused to traverse their divergent paths in unison to effect the desired spacing.
3. A machine for setting lacing hooks, comprising a plurality of hook-supporting members, a plurality of anvils adapted to cooperate therewith to set a plurality of hooks in one operation, said supporting members and anvils being laterally movable for varying the spacing of the hooks, and means for moving said supporting members edgewise after a setting operation to remove them from the hooks, said means being adapted to preserve operative relation with the supporting members in whatsoever position they are adjusted.
4. A machine for setting lacing hooks, comprising a plurality of movable supports, a plurality of plates for supporting hooks, said plates being movably mounted on said supports, a plurality of anvils adapted to coact with said plates to set a plurality of hooks, said supports and anvils being movable to vary the spacing of the hooks, operating members on said supports for retracting said plates edgewise from the hooks after a setting operation, and means adapted to coact with said operating members in whatsoever position they are adjusted to actuate them for the purpose specified.
5. A machine for setting lacing hooks, comprising two supports one of which is movable toward and from the other, said supports having divergent guides, two sets of slides arranged in said guides, hook-supporting plates on the slides of one set, anvils on the slides of the other set, said plates and anvils being adapted to coact to set a plurality of hooks, and means connecting the slides of both sets for moving them in unison in their guides to vary the spacing of the hooks.
6. A machine for setting lacing hooks, comprising two supports, one of which is movable toward and from the other, a plurality of hook-supporting members movably mounted upon one of said supports, a plurality of anvils movably mounted upon the other support, said supports having divergent guides whereby said hook-supporting members and said anvils are guided laterally with reference to their operating movement, and means for adjusting the several hook-supporting members and anvils in their guides.
7. A machine for setting lacing hooks, comprising hook-setting mechanism, mechanism for loading said setting mechanism with hooks ready for insertion in the work, automatic means for stopping said setting mechanism, and means operated by said setting mechanism for rendering said loading mechanism active when said setting mechanism is stopped.
8. A machine for setting lacing hooks, comprising hook-setting mechanism, mecha-

nism for loading said setting mechanism with hooks ready for insertion in the work, disconnectible driving means for said setting mechanism, disconnectible driving means for said loading mechanism, automatic means for disconnecting said first driving means, and means actuated by said first driving means for coupling said second driving means to drive the loading mechanism when the setting means is disconnected.

9. A machine for setting lacing hooks, comprising hook-setting mechanism, mechanism for loading said setting mechanism with hooks ready for insertion in the work, disconnectible driving means for said setting mechanism, disconnectible driving means for said loading mechanism, automatic means for disconnecting said first driving means at the end of one cycle, and controlling means actuated by said first driving means for effecting the connection of said second driving means when the first driving means has completed one cycle, said controlling means being adapted to disconnect said second driving means at the end of a cycle.

10. A machine for setting lacing hooks, comprising a plurality of hook-supporting members, a hook reservoir, a hook raceway movable to operative relation with first one and then another of said hook-supporting members, said raceway being adapted to register, in one position, with said reservoir to receive hooks therefrom, and means for transferring hooks, one at a time, from said raceway to said hook-supporting members.

11. A machine for setting lacing hooks, comprising a plurality of hook-supporting members and anvils for inserting a plurality of hooks in one operation, and means for placing hooks one at a time in operative position upon said hook-supporting members.

12. A machine for setting lacing hooks, comprising a plurality of hook-supporting members and anvils for inserting a plurality of hooks in one operation, a hook carrier adapted to deposit hooks one at a time upon the several hook-supporting members, and means for supplying hooks to said carrier.

13. A machine for setting lacing hooks, comprising a plurality of hook-supporting members and anvils for inserting a plurality of hooks in one operation, said hook-supporting members and anvils being laterally adjustable for varying the spacing of the hooks, a hook carrier adapted to deposit hooks one at a time upon the several supporting members in their various adjusted positions, and means for supplying hooks to said carrier.

14. A machine for setting lacing hooks, comprising a plurality of hook-supporting members and anvils for inserting a plurality of hooks in one operation, a hook raceway, and a hook carrier adapted to take hooks

one at a time from said raceway and deposit them on the several hook-supporting members.

15. A machine for setting lacing hooks, comprising a plurality of hook-supporting members and anvils disposed about an axis, said members and anvils being adjustable toward and from said axis in divergent paths to vary the spacing of the hooks, a hook raceway arranged so that its delivery end is adjacent said axis, a hook carrier movable about said axis and movable transversely thereof for taking hooks one by one from said raceway and depositing them on said hook-supporting members, and yielding means adapted to impart maximum hook-carrying movement to said carrier, and to yield when the movement of the carrier is limited by the hook-supporting members.
20. 16. A machine for setting lacing hooks, comprising setting mechanism, a raceway for hooks, a carrier for carrying a hook to the setting mechanism, and a movable member adapted to receive a hook from the raceway and hold the hook in position to be taken by said carrier, said movable member being adapted to be displaced from hook-receiving position by said carrier.

25. 17. A machine for setting lacing hooks, comprising setting mechanism, a carrier adapted to carry a hook to said mechanism, a hook raceway the end of which is arranged to deliver a hook in the path of said carrier and to be closed by said carrier, and a movable member adapted to register with the end of the raceway to receive a hook and support it in the path of said carrier, said movable member being adapted to move out of the path of said carrier to permit the carrier to move to the setting mechanism.

30. 18. A machine for setting lacing hooks, comprising setting mechanism, a hook raceway, a spring-tensioned member adapted normally to register with the end of the raceway to receive a hook therefrom and support the hook, and a reciprocatory hook carrier adapted to take the hook from said spring tensioned member to the setting mechanism.

35. 19. A machine for setting lacing hooks, comprising setting mechanism, a hook raceway, and a carrier for supporting and carrying a hook from the raceway to the setting mechanism, said carrier comprising a support adapted to engage the head of a hook, and a co-operative members adapted to straddle and engage the tubular shank of the hook, the shank engaging surfaces of said members being substantially parallel to the carrying movement of said carrier.

40. 20. A machine for setting lacing hooks, comprising two supports one of which is movable toward and from the other, said supports having divergent guides extending transversely to the relative movement of the

supports, slides movable in said guides, co-operative hook-setting devices on said slides, said slides having gear teeth, rotatable toothed members engaging the teeth of said slides, and means for operating said rotatable toothed members to adjust said slides.

45. 21. A machine for setting lacing hooks, comprising two supports one of which is movable toward and from the other, said supports having divergent guides extending transversely to the relative movement of the supports, slides movable in said guides, co-operative hook-setting devices on said slides, said slides having gear teeth, two toothed racks mounted respectively on said supports, rotatable toothed gears for transmitting movement from said racks to said slides, and means for positioning said racks to adjust said hook-setting devices.

50. 22. In a machine for setting lacing hooks, a support, a plurality of slides thereon, hook-supporting members movably mounted on said slides, hook-setting devices adapted to co-operate with said hook-supporting members, said slides and said hook-setting devices being adjustable laterally for varying the spacing of the hooks, means on said slides for retracting said hook-supporting members from the hooks, and means for operating said retracting means.

55. 23. In a machine for setting lacing hooks, a plurality of hook-supporting members and anvils adjustable in divergent paths to vary the spacing of the hooks, a hook carrier adapted to deposit hooks one at a time upon the several hook-supporting members, and means for supplying hooks to said carrier.

60. 24. In a machine for setting lacing hooks, a plurality of hook-supporting members and anvils adjustable in divergent paths to vary the spacing of the hooks, a hook carrier adapted to deposit hooks one at a time upon the several hook-supporting members, means for operating said carrier, said means having provisions for varying the movement of said carrier to compensate for different adjustments of said hook-supporting members, and means for supplying hooks to said carrier.

65. 25. In a machine for setting lacing hooks, a reciprocatory hook carrier, means for supplying hooks to said carrier, a plurality of hook-supporting members and anvils adjustable in divergent paths toward and from said carrier, and means for operating said carrier to deposit hooks one at a time upon said supporting members, said operating means having provisions for varying the movements of said carrier to compensate for various adjustments of said hook-supporting members.

70. 26. In a machine for setting lacing hooks, a hook-supporting member, an anvil, a hook-setting device for co-operating with said anvil, and means for carrying a hook from

said supporting member to said setting device.

27. In a machine for setting lacing hooks, a hook-supporting member, an anvil, a hook-setting device for coöperating with said anvil, means for carrying a hook from said supporting member to said setting device, and a raceway the delivery end of which is arranged to deliver a hook to said supporting member.

28. In a machine for setting lacing hooks, a hook-setting device, a hook raceway, a hook-supporting member arranged to receive a hook from the delivery end of said raceway, and a hook carrier movable transversely of the delivery end of said raceway for carrying a hook from said supporting member to said setting device.

29. In a machine for setting lacing hooks, a hook-setting device, a hook raceway, a hook support arranged to receive a hook from the delivery end of said raceway, said hook support being adapted to support a hook by occupying the throat of the hook, and a hook carrier movable between said support and said delivery end for carrying a hook from said support to said setting device, said support being displaceable to enable said carrier to perform its carrying movement.

30. In a machine for setting lacing hooks, coöperative hook-setting devices, a hook raceway, a pivotally mounted hook-supporting member whose free end is adapted to abut against the delivery end of said raceway in position to receive a hook therefrom, and a hook carrier movable between the raceway and hook-supporting member, said carrier being adapted to detach a hook from said supporting member and carry the hook to one of said setting devices.

31. In a machine for setting lacing hooks, coöperative hook-setting devices, a hook raceway, a movable hook-supporting member adapted to register with the delivery end of the raceway to receive a hook therefrom, a carrier adapted to detach the hook from said supporting member and carry the hook to one of said setting devices, and means for positioning the hook on said supporting member with relation to said carrier.

32. In a machine for setting lacing hooks, coöperative hook-setting devices, a hook raceway, a movable hook-supporting member adapted to register with the delivery end of the raceway to receive a hook therefrom, and a carrier adapted to detach the hook from said supporting member and carry the hook to one of said setting devices, said supporting member having an abutment for positioning the hook with relation to said carrier.

33. In a machine for setting lacing hooks, a plurality of anvils and coöperative setting devices, a hook raceway, a hook-supporting member adapted to receive hooks from said raceway, and means for detaching hooks from said supporting member and depositing the hooks on said setting devices.

34. In a machine for setting lacing hooks, a plurality of anvils and coöperative hook-setting devices, a hook raceway, a hook-supporting member adapted to receive hooks from said raceway, a hook carrier, and means for moving said carrier from said hook-supporting member to each of said setting devices in turn, said carrier being adapted to detach hooks from said supporting member and deposit them on said setting devices.

35. A machine for setting fasteners, having, in combination, means for feeding fasteners, a gang of fastener-carrying devices, and means arranged and operated to transfer fasteners one after another from said feeding means to said carrying devices successively.

36. A machine for setting fasteners, having, in combination, a gang of fastener-setting devices, and mechanism arranged to supply fasteners to said devices successively, said mechanism being adapted to be set in operation automatically and to come to rest automatically after all said devices have been supplied.

37. A machine for setting fasteners, having in combination, means for feeding fasteners, a gang of fastener-carrying devices, and means constructed and arranged to transfer to said devices one after another from said feeding means, a fastener for each of said devices.

38. A machine for setting fasteners, having in combination, a gang of setting devices, and mechanism constructed and arranged to supply to said devices one after another, a fastener for each device, said mechanism being constructed and arranged to be set in operation automatically and to come to rest automatically after all of said devices have been supplied.

39. A machine for setting lacing hooks, comprising a plurality of hook-supporting members and anvils for inserting a plurality of hooks in one operation, and means for placing in operative position on said hook supporting members one after another, a hook for each supporting member.

In testimony whereof I have affixed my signature, in presence of two witnesses.

ANDREW RAICHE.
